UNITED STATES PATENT OFFICE.

WILLIAM DOUGHERTY AND CARLETON Y. JAMES, OF CHESTER, PENNSYLVANIA.

WATER-TUBE BOILER.

No. 902,951.

Specification of Letters Patent.

Patented Nov. 3, 1908.

Application filed July 18, 1907. Serial No. 384,316.

To all whom it may concern:

Be it known that we, WILLIAM DOUGHERTY and CARLETON Y. JAMES, citizens of the United States, residing at Chester, in the 5 county of Delaware and State of Pennsylvania, have invented certain new and useful Improvements in Water - Tube Boilers, of which the following is a specification.

Our invention relates to water tube boilers, 10 and has for its object the production of a steam generator of the class in which the water is heated in tubes directly exposed to the burning furnace gases, those tubes having special form and particular arrangement 15 whereby it is believed that greater economy of construction is attained, and leaking at the joints of the tubes with the end boxes and drum under expansion while steaming prevented.

20 We accomplish the stated object by fashioning and associating the parts as illustrated in the accompanying drawings, of which

Figure 1 represents a vertical section lengthwise, and Fig. 2 shows an end view 25 partly in vertical section.

Like reference letters are used to designate like parts throughout the specification and drawings.

In the drawings the furnace grate is 30 marked A, the front of the boiler setting is designated by the letter B and the back by C. The bridge wall is referred to by the letter D.

The longitudinal drum of the boiler is designated E, and is in open communication 35 with the front end box F and the rear end box G as is customary.

The tubes H and J have substantially the same form. That is to say, each has a substantially horizontal straight portion opening 40 into an end box, and a vertical portion opening into the drum. In addition to those features the outer-lying tubes J curve laterally inward at the top for their connections with the drum, as shown in Fig. 2.

45 Suitably placed baffle plates K and L erected upon the bridge wall, and like horizontal and vertical baffle plates M and N direct the products of combustion from the grate bars through the system of tubes as indicated by the arrows.

50 It will be observed that in the construction constituting our invention, the relatively horizontal portions of the tubes have each a slight upward inclination from the end box 55 to which it is attached.

The tubes are arranged in vertical and hori-

zontal rows. Those tubes which open into an end box near the top of the box, that is to say, nearest the drum E, extend to a point slightly beyond the middle of the drum where 60 they are connected with the drum in suitable orifices, the centers of those orifices for all the tubes in the uppermost row of tubes lying in the same vertical plane. Observed from the side, therefore, as in Fig. 1, the ends of tubes 65 appear to cross each other. The next lower row of tubes opening into either end box, extend still further beyond the middle of drum E, and the vertical portions of those tubes are in like manner secured in a row of orifices 70 in the drum parallel to the row of orifices in which the first mentioned or uppermost row of tubes are secured. In regular, spaced order, each lower row of tubes extends further beyond the middle of the drum than the row 75 of tubes next above, and finally, the lowest row of tubes, and the longest, are connected with the drum E near the tops of the end boxes.

In any tube there is but a single turn, and 80 that is made a gradual bend. The result is an extremely rapid circulation in the tubes, so rapid, in fact, as to practically eliminate the deposit of scale therein, and to materially increase the amount of steam generated in 85 a given time beyond the steaming capacity of water tube boilers in the same general class with which we are acquainted.

Having now described our invention and 90 explained the mode of its operation, what we claim is—

In a water tube boiler, the combination with the furnace grate, of a longitudinal steam drum, end boxes opening into the drum near the ends of the drum and arranged vertically, the body of said end boxes being constructed greater in width than the diameter of the drum, bent tubes arranged lengthwise below the drum and each having a horizontal portion connected with an end box and a vertical portion connected with the drum, and each of said tubes having a portion extending above the furnace grate, substantially as shown and described.

105 In testimony whereof we affix our signatures in presence of two witnesses.

WILLIAM DOUGHERTY.
CARLETON Y. JAMES.
